UNITED STATES PATENT OFFICE

1,986,151

FAN

William W. Johnston, Dayton, Ohio, assignor of
one-half to International Engineering, Inc.,
Dayton, Ohio, a corporation of Ohio

Application August 5, 1933, Serial No. 683,831

14 Claims. (Cl. 170—166)

This invention relates to fans and, in particular, to that type of fan used for ventilation or cooling purposes.

One object of my invention is to provide a fan having the capacity to move a much larger volume of air at the periphery than at the center during a given period of time, this being greater than the normal increase due merely to the increased linear speed at the periphery.

Another object is to provide such a fan wherein the rate of increase in the volume of air moved is discontinuous, increasing gradually from the center outward to a certain point and then increasing suddenly by a large amount.

Another object is to provide such a fan wherein in the center portion moves air at a low rate where the motor obstructs the passage thereof, and at a high rate at the margin where there is no such obstruction.

Another object is to provide such a fan having main and subsidiary blades which may be cast in a single piece.

Another object is to provide such a fan with main blades having a stream-lined cross section in order that they may expend the minimum amount of power upon edge resistance losses and the maximum amount in moving the air.

Another object is to provide such a fan having main blades which likewise serve as spokes for a rim which carries the subsidiary blades, so that all parts of the fan except the hub and rim perform active air-moving functions.

Another object is to provide a fan which moves a larger volume of air for the space occupied than is moved by a fan having main propelling blades only.

Another object is to provide the maximum blade area at the point of maximum speed with the least resistance to air movement so as to drive at high speed a cylinder of air in the area where there is the least resistance because there is no impediment in the road of the air, such as driving the motor, etc.

It is a further object to eliminate tip eddies by removing the tips of the outer, supplementary blades and of the major blades, thereby increasing the air flow without danger of return flow.

It is a further object to provide a large area of blades in this outer high speed area for moving the air.

In the drawings:

Figure 1 is a front view of the fan of my invention.

Figure 2 is an end view of an outer subsidiary

blade thereof, looking in the direction of the arrows 2—2 in Figure 1.

Figure 3 is a cross section through a main blade along the line 3—3 of Figure 1.

Figure 4 is a cross section through an inner subsidiary blade, along the line 4—4 in Figure 1.

Figure 5 is a side elevation of the fan shown in Figure 1.

Figure 6 is a front view of a modified form of fan having main and outer subsidiary blades only.

Figure 7 is a front view of a modified form of fan having main and inner subsidiary blades only.

Referring to the drawings in detail, the fan shown in Figure 1 consists of a hub 1 having a flanged portion 2 and a central portion 3 through which passes the shaft bore 4 provided with the keyway 5. The drive-shaft (not shown) is provided with a corresponding slot so that a key will engage the latter and the keyway 5, thus fixedly attaching the fan to the drive shaft. The drive shaft is preferably rotated by an electric motor, which may be placed immediately behind the hub 1 and mounted upon a stream-lined cross member behind the fan.

Arranged radially outward from the hub 1 are the main fan blades 6 which serve not only as air propellers but also as spokes to support a rim 7 connecting their peripheral ends. The rim 7 is of annular shape, and is provided with a plurality of subsidiary outer and inner fan blades 8 and 9 respectively.

As shown in Figures 2, 3 and 4, the fan blades are of stream-lined or "air-foil" construction having their entering edges blunt and their trailing edges sharp. This construction causes the fan blades to pass through the air and consume a minimum amount of power in the edge resistance thereby set up. Consequently, the maximum part of the power consumed in driving the fan goes into the useful work of moving the air for ventilation or cooling purposes. The fan blades are also preferably of helical or screw construction, so that the angle of inclination of the fan blade to the axis of rotation varies at different points between the tip and base of the fan blade. This screw construction adds to the efficiency of the fan blade.

The fan construction shown is preferably cast in one piece. This one-piece construction adds to the strength of the fan, decreases the cost of manufacture, reduces the possibility of derangement or breakdown during operation and enhances the appearance since there are no pockets or crevices formed, which might harbor dirt or grease.

It will be seen from Figure 1 and from a consideration of the behavior of fan blades that the rate of air volume moved by the fan increases slowly as the point considered passes from the hub 1 to a circular line tangent to the tips 10 of the subsidiary blades 9. At this point, however, the subsidiary blades 9 add their propelling effect to that already created by the main blades 6, with the result that there is a sudden increase in the rate of air volume moved by the fan at this point. The rate of air volume moved again increases regularly as the point considered passes from the tips 10 of the inner subsidiary blade to the rim 7 and thence to the tips 11 of the outer subsidiary blades 8. It will be seen, therefore, that in the central space immediately surrounding and in back of the hub 1, the rate of air volume moved is comparatively low, but, as this space is generally obstructed by the driving motor, it would be inadvisable to provide a high rate of air propulsion therein. In the space outward from the tips 10 of the inner subsidiary blades 9, however, the motor obstruction is lacking, and consequently it is desirable to increase the propelling effect of the fan so that the volume of air moved thereby is much larger for the space occupied by the fan than would be the case if the main propelling blades 6 alone were used.

The modified form of fan shown in Figure 6 is similar to the form shown in Figure 1, but possesses main blades 6 and outer subsidiary blades 8, the inner subsidiary blades 9 being omitted. The modified form shown in Figure 7 is likewise similar to that of Figure 1, except that the fan has main blades 6 and inner subsidiary blades 9, the outer subsidiary blades 8 being omitted. Both of these modified forms of fan obey the same principles of operation shown in Figure 1, but it will be obvious that the rate of air volume moved will vary in a different manner from the form of Figure 1. The rate of increase thereof in Figure 6, for example, will be regular and gradual until the rim 7 is reached, and then suddenly increases as the additional effect of the outer peripheral blades 8 is brought into play. The form in Figure 7 will have a rate of increase similar to that of Figure 1 until the rim 7 is reached, but the added effect of the outer subsidiary blades 8 is, of course, lacking since these outer blades 8 themselves are absent.

While it is preferably to cast or otherwise make the fan blade of my invention in a single piece, it is understood that it might be made in a plurality of pieces without departing from the scope or spirit of my invention.

It will be understood that I desire to comprehend within my invention such modifications as may be necessary to adapt it to varying conditions and uses.

Having thus fully described my invention, what I claim as new and desire to secure by Letters Patent is:

1. A fan comprising a plurality of main blades, a support carried by said main blades, and subsidiary blades carried by said support, the entering edges of said blades being relatively blunt compared with the trailing edges thereof.

2. A fan comprising a plurality of main blades, a support carried by said main blades, and subsidiary blades carried by said support, said subsidiary blades being directed radially from said support, the entering edges of said blades being relatively blunt compared with the trailing edges thereof.

3. A fan comprising a hub, a plurality of main

blades attached to said hub, a support carried by said main blades near the tips thereof, and tapered subsidiary blades carried by said support, the entering edges of said blades being relatively blunt compared with the trailing edges thereof. 5

4. A fan comprising a main blade and a subsidiary blade associated with said main blade, the entering edges of said blades being relatively blunt compared with the trailing edges thereof, 10 whereby said blades are streamlined to reduce the edge resistance thereof.

5. A fan comprising a main blade and a subsidiary blade associated with said main blade, the median planes of said blades having a variable angle with the axis of rotation thereof between said axis and the tips of said blades, the entering edges of said blades being relatively blunt compared with the trailing edges thereof. 15

6. A fan comprising a hub, a plurality of main blades attached to said hub, a support carried by said main blades near the tips thereof, and subsidiary blades carried by said support, said subsidiary blades being alternately directed outwardly and inwardly from said support, the entering edges of said blades being relatively blunt compared with the trailing edges thereof. 20

7. A fan comprising a hub, a plurality of main blades attached to said hub, a support carried by said main blades near the tips thereof, and subsidiary blades carried by said support, said subsidiary blades being alternately directed outwardly and inwardly from said support in a radial direction, the entering edges of said blades being relatively blunt compared with the trailing edges thereof. 30

8. In a fan, a hub and a plurality of major blades radiating therefrom, an annular support bridging the ends of the said blades, and a plurality of stub blades mounted thereon, the entering edges of said blades being relatively blunt compared with the trailing edges thereof. 40

9. In a fan, a hub and a plurality of major blades radiating therefrom, an annular support bridging the ends of the said blades, and a plurality of stub blades mounted thereon being greater in number than the major blades, the entering edges of said blades being relatively blunt compared with the trailing edges thereof. 45

10. In a fan, a hub and a plurality of major blades radiating therefrom, an annular support bridging the ends of the said blades, and a plurality of tapered supplementary stub blades mounted on the support and extending in opposite directions, said stub blades being greater in number than the major blades. 50

11. In combination, a hub, a plurality of major fan blades, and a plurality of oppositely disposed supplementary blades lesser in length but greater in number than the major blades, said supplementary blades being tapered. 60

12. In combination, a hub, a plurality of major fan blades, and a plurality of oppositely disposed supplementary blades lesser in length but greater in number than the major blades, said supplementary blades being tapered toward their ends. 65

13. In combination, a fan, a hub, a plurality of major blades, a ring support mounted on the ends thereof, a plurality of radially disposed supplementary blades extending on the outside of said ring outwardly, and a plurality of such blades extending on the inside of said ring inwardly, the total number of said supplementary 70

75

blades on either the outside or inside the ring being greater in number than the major blades, said outwardly extending supplementary blades having square ends and the inwardly extending blades having tapered ends.

5 14. In a fan, a hub, a plurality of relatively

long major blades having their tips cut away, a ring mounted on the ends of said blades, and a plurality of inwardly extending tapered supplementary blades of lesser length than the major blades but greater in number.

5 WILLIAM W. JOHNSTON.
